UNITED STATES PATENT OFFICE.

ANTONIO PAJALIC, OF DETROIT, MICHIGAN.

VENTILATOR.

Application filed June 8, 1921. Serial No. 475,911.

To all whom it may concern:

Be it known that I, ANTONIO PAJALIC, a citizen of the United States, and a resident of Detroit, in the county of Wayne and State of Michigan, have invented certain new and useful Improvements in Ventilators, of which the following is a specification.

This invention relates to ventilators, and 10 is an improvement over the construction illustrated in my pending application for patent, Serial No. 416,918, filed October 14, 1920.

An important object of this invention is 15 to provide novel means for rotatably supporting the body of the ventilator so that the same may freely rotate as the result of the passage of air through the same.

A further object of the invention is to 20 provide a ventilator of the class described which is quiet, efficient in operation, and cheap to manufacture.

Other objects and advantages of the invention will be apparent during the course 25 of the following description.

In the accompanying drawings, forming a part of this application and in which like numerals are employed to designate like parts throughout the same,

30 Figure 1 is a vertical sectional view through the improved ventilator;

Figure 2 is a horizontal sectional view taken on line 2—2 of Figure 1;

35 Figure 3 is a horizontal sectional view taken on line 3—3 of Figure 1;

Figure 4 is a detail section through a lubricator embodied in the invention, and

40 Figure 5 is a fragmentary perspective of another lubricator embodied in the invention.

Figure 6 is a section through the lubricator illustrated in Figure 5.

In the drawings, wherein for the purpose of illustration is shown a preferred embodiment of the invention, the numeral 5 designates a stack which may have communication with the interior of a room within a building and which is provided with a damper 6 pivoted as indicated at 7. A chain 8 is connected to one side of the damper and extends to a convenient point from where the same may be operated. The opposite side of the damper 6 is provided with a weight 9 which swings the damper to its 55 open position when the chain 8 is released.

As illustrated in Figure 1, the stack 5

is provided at a point spaced from its upper end with upper and lower spiders 10 and 12 respectively which are formed with aligned bearings 14 and 15 respectively for the reception of a tubular standard designated by the numeral 16. The standard 16 which extends above the stack for a substantial distance is securely connected to the bearings 14 and 15 by means of set screws 17.

The body 20 of the ventilator includes an annulus 21 having its lower end disposed below the upper end of the stack 5 and spaced from the same so as to permit a quantity of air to flow upwardly into the 70 ventilator between the annulus 21 and the side of the stack. As illustrated in Figure 1, an annular series of longitudinally curved ribs 22 are secured at their lower ends to the outer side of the annulus and at their upper 75 ends to an annular flange 26. The annular flange 26 is in turn secured at its lower end to the upper portion of a sleeve 28 or central conduit which extends centrally through the ventilator and terminates in the plane 80 of the annulus 21, the said sleeve 28 having its ends open to permit of the free passage of air through the same. The annular series of ribs are further held in position by means of a second annular flange 29 secured 85 to the upper portion of the sleeve 28 and extending downwardly into contact with the upper portions of the ribs 22.

A ventilator head generally designated by the numeral 25 is mounted upon the annular flange 29 and comprises a plurality of V-shaped baffles 30 arranged outwardly of the openings 31 formed in the adjacent portion of the sleeve 28. By arranging the V-shaped baffles outwardly of the openings 31 and in 95 spaced relation to the same, rain and snow is effectively excluded from the interior of the sleeve 28. The rain is further excluded from the sleeve 28 by means of an annular series of arcuate baffles 32 arranged outwardly of and overlapping the sides of the V-shaped baffles 30, whereby to prevent the rain from entering the sleeve by way of the openings between the V-shaped baffles 30.

The top plate 34 of the head 25 is mounted 100 upon the baffles 30 and 32 and supports a cone-shaped crown 35 having depending ears 36 arranged outwardly of the arcuate baffles 32. The depending ears 36 not only add to the appearance of the ventilator but aid in 110 excluding the rain from the sleeve 28.

The crown 35 carries a depending bearing

pin 40 which rotatably fits within a bearing opening in the closed upper end of the standard 16. A lubricant is supplied to the bearing 40 from a cup 41 formed on the upper 5 end of the standard and having a detachable cap 42, by means of which the lubricator may be periodically filled. An opening 43 extends through the depending bearing pin 40 and supplies a lubricant to the bearing 10 so that the operation of the ventilator may be rendered noiseless.

The tubular standard 16 is enclosed within the casing 46 extending downwardly from the crown 35 and having its lower end provided with a lubricant cup 47 adapted for supplying a lubricant to an annular series of ball bearings 48 or other anti-friction elements between the lower end of the tubular casing 46 and a collar 49 secured to the 20 standard by means of a set screw 50. The collar 49 is formed with an annular groove 51 which freely receives a set screw 52 carried by a depending flange 54 on the lower portion of the casing 46. The set screw 52 prevents 25 the upward movement of the sleeve on the standard when the ventilator is subject to strong currents of air.

As illustrated in Figure 1 the stack 5 is provided with a plurality of inwardly struck 30 lugs 68 which provide openings 69 for the passage of air from the outside into the stack. The openings 69 are surrounded by an annular flange 70 which prevents rain from passing through the openings. It will 35 be seen that the annular flange 70 is L-shaped in cross section.

In operation, the air striking the annular series of ribs 22 causes the ventilator to rotate with the result that the casing 46 and 40 the head 25 will be rotated. The draft created by the movement of the air between the annulus 21 and the upper end of the stack causes the foul air to be drawn up through the stack and either into the space 45 between the ribs or through the sleeve 28. The air drawn into the sleeve 28 passes outwardly through the openings 31 and past the sides of the baffles 30 and 32.

In operation the ventilator is extremely 50 quiet and operates with a maximum of efficiency. No motor is necessary for the operation of the ventilator and by means of this construction the same may be made in extremely large sizes for use in theaters and 55 other places capable of holding a large number of people and wherein it is necessary to provide for the constant circulation of air.

One of the principal features of my invention resides in the fact that the foul air 60 passing upwardly through the central conduit is not interfered with by strong air currents which may pass through the ribs 22. In other words, a strong draft passing 65 through the outer side of the ventilator will

not prevent the upward movement of the air to the central conduit. This construction provides a second ventilator arranged within the outer ventilator comprised by the series of longitudinally curved rims 22.

With reference to the foregoing description taken in connection with the accompanying drawing it will be apparent that a ventilator constructed in accordance with this invention may be readily attached to a 75 building and in use will permit the foul air to be effectively scavenged. Also the body 20 of the ventilator may be readily removed by loosening the set screws 50 and 52 whereupon the body may be elevated for disconnecting the sleeve 28 from the tubular standard 16. As illustrated in Figure 1 the body 20 is connected at its lower end to the sleeve or central air conduit by means of a plurality of radial spokes 117 extended 80 through the annulus 21, through the central conduit and into the enlarged lower portion of the sleeve 46.

I claim:—

1. A ventilator comprising a body, a 90 sleeve arranged therein, a tubular casing extended through said sleeve, a standard extended upwardly through said casing, the upper portion of said sleeve being formed with openings, V-shaped baffles arranged 95 outwardly of said openings, arcuate baffles arranged outwardly of said V-shaped baffles, a top plate secured to said baffles, and a plurality of radial spokes connecting the lower portion of said body and the lower portion 100 of said tubular casing.

2. A ventilator comprising a tubular body, a supporting standard extending upwardly from said body, an air conducting sleeve surrounding said standard and being in communication with said tubular body to receive air from the same, an air discharge member arranged at the upper end of said air conducting sleeve and being in communication with the same, an annular series of 105 spaced ribs surrounding said sleeve and forming an annular air passage in communication with said tubular body, said air passage surrounding said air conducting sleeve, and a tubular casing supporting said ribs 110 and sleeve and mounted on said standard.

3. A ventilator comprising a tubular body, a supporting standard extending upwardly from the body, an air conducting sleeve surrounding said standard and being in communication with said tubular body to receive air from the same, an air discharge member arranged at the upper end of said air conducting sleeve and being in communication with the same, an annular series of 115 spaced ribs surrounding said sleeve and forming an annular air passage in communication with said tubular body, said annular air passage surrounding said air conducting sleeve, a tubular casing supporting said 120

sleeve and ribs and mounted on said standard, and a plurality of inwardly extending arms connected to said tubular body and having a bearing receiving said standard.

5. A ventilator comprising a tubular body, a supporting standard extending upwardly from said body, an air conducting sleeve surrounding said standard and being in communication with said tubular body to receive air from the same, an air discharge member arranged at the upper end of said

air conducting sleeve and being in communication with the same, an annular series of spaced ribs surrounding said sleeve and forming an annular air passage in communication with said tubular body, a tubular casting supporting said ribs and said sleeve and mounted on said standard, said annular air passage surrounding said air conducting sleeve, and means carried by said tubular body to rotatably support said shaft. 15 20

ANTONIO PAJALIC.
